SELF-SEATING GASKET

Edward M. O'Donnell, San Francisco, Calif.

Application September 5, 1939, Serial No. 293,411

1 Claim. (Cl. 257—240)

This invention relates to packing gaskets of the type employed to prevent leakage from one pressure chamber to another, and especially to a gasket or packing strip which is self-seating and which is maintained on its seat by the pressure maintained on a fluid or liquid circulated through the chamber.

In the operation of heat exchangers or like apparatus, in which the heads disposed at the opposite ends of the heating chamber are cross-ribbed to form a multiplicity of chambers to permit the liquid or other substance treated to be circulated back and forth through the tubes within the heat exchanger, considerable trouble is encountered in preventing leakage or short circuiting of the liquid between the chambers, as it is almost impossible to maintain uniform seats for the reception of packing gaskets, due to variations in expansion and contraction of the several parts forming the heat exchanger, and also due to pressure variations at different points within the heat exchanger.

The object of the present invention is generally to improve and simplify the construction and operation of heat exchangers and like apparatus, and especially to provide a gasket or packing strip which is self-seating and which is maintained in its seat by fluid pressure.

The invention is shown by way of illustration in the accompanying drawings, in which

Fig. 1 is a central, vertical, longitudinal section through a heat exchanger;

Fig. 2 is an end view looking at the interior face of one of the exterior heads;

Fig. 3 is a perspective view of a portion of one of the packing strips, showing the manner in which it is retained; and

Fig. 4 is an enlarged detail cross sectional view showing a modified form of packing gasket interposed between one of the heads and tube sheets.

Referring to the drawings in detail, and particularly to Fig. 1, A indicates a cylindrical elongated housing which may be constructed of steel, cast iron, or any other suitable material. Formed at one end of the housing is an annular flange 2 and secured thereto by bolts 3 or other suitable means is a tube sheet 4. Slidably mounted on the opposite end of the housing is a floating head member 5. This head member is circular in shape and angular in cross section. It forms a support for a second tube sheet 4a, said tube sheet being secured by bolts 6 or the like. Secured between the tube sheets 4 and 4a are a plurality of tubes 7. These tubes are preferably constructed of copper, or like materials; hence if

the housing is constructed of steel and the tubes of copper the difference in coefficients of expansion between the same is considerable. It is for this reason that the floating head 5 has been provided for the support of the tube sheet 4a. By providing the floating head, free expansion and contraction of the tubes 7 can take place without throwing any stress or strain on the housing, or the tube sheets.

In as much as the tubes 7 are heated by steam, or a similar medium, admitted through the connection shown at 8 under pressure, considerable leakage might occur between the floating head and the housing, and a seal in the form of a flexible ring 9, which is S-shaped in cross section, is employed. The sealing member is secured at one end to an annular flange 10 formed on the housing by means of a clamping ring and bolts 11, and the opposite end is secured to the tube sheet 4a by a clamping ring and bolts 12. The joints formed by the bolts 11 and 12 and the cooperating clamping rings are leak-proof, and any pressure desired may thus be employed.

In the operation of heat exchangers of the character here disclosed, accessibility for inspection, cleaning, sterilizing, repair, etc., is exceedingly important, as the apparatus must be thoroughly cleaned, inspected and sterilized at least once during each twenty-four hours of operation. To promote such accessibility and to facilitate repairs the tube sheets have been made removable and renewable, so that if either sheet should crack or become otherwise impaired it may be removed merely by releasing the bolts 3 or 12. To facilitate accessibility for cleaning, inspection and so on, removable heads B and C are provided. These are secured in place by bolts 14 and wing nuts 15, and hinges may also be provided, about which the heads may be swung, but they are not disclosed in the present instance as they form no part of the invention. The inner surface of the head B is provided with a transverse rib or partition wall 16, which divides the head into two chambers 17 and 18. The head C is provided with two cross-ribs, thereby forming three chambers 19, 20 and 21. The liquid to be heated or otherwise treated enters the chambers 19 through an elbow connection 22. It flows through the tubes 23 and 24 in the direction of the arrows into chamber 17, then through tube 25 into chamber 20, then through tube 26 into chamber 18, and finally through tubes 27 and 28 into chamber 21, and out through an elbow 29. In actual practice considerable difficulty has been experienced in maintaining a tight seat be-

tween the cross-ribs or partition walls 16, 17 and 18 and the respective tube sheets 4 and 4a. A tight seat at these points is essential, as leakage or short circuiting of the liquid passing through the heat exchanger will take place from one chamber to another unless tight seats are maintained. Plainly speaking, if the liquid to be circulated and heated can leak or flow from one chamber to another without passing through the heat exchanging tubes, the proper temperature will not be obtained. In most instances, the liquid to be circulated and heated is maintained under considerable pressure, for instance, 80 lbs. gauge or more, and obviously the higher the pressure the greater the leakage.

In the structure here shown, a gasket or packing strip 30 is employed which is self-seating and which is held against the seat by the pressure maintained on the liquid. This is accomplished as follows:

Referring to the drawings, and particularly to Fig. 3, it will be noted that each cross-rib is provided with a side bar 31, and that each side bar is maintained in spaced relation to its cross-rib by spacer lugs 32 welded or otherwise secured to the respective members. The inner face 33 of each rib and side bar is machined or finished to clear the adjacent tube sheet by, for instance, $\frac{1}{16}$ of an inch, when the heads B and C are closed and tightened into place against their gaskets 40. The gaskets or packing strips 30 may be made of rubber or any suitable material. They are placed between each cross-rib and cooperating side bar, and are frictionally held in place between them. They may project beyond the faces 33 when in place, and as such they will engage the adjacent faces of the tube sheets when the heads are applied and tightened, but such engagement can not be depended upon, as the tube sheets and the heads proper are subject to variations in both temperature and pressure, and a uniform seating surface can therefore not be relied upon. The moment liquid is introduced under pressure, and starts circulating, each gasket or packing strip will seat against its adjacent tube sheet, as the major pressure will be exerted on the outer face or end 35, as these faces are fully exposed to the liquid under pressure, due to the openings 36 formed between the spacing lugs 32, and seating of each gasket is thus insured, regardless of any irregularity in the seating surface.

In an apparatus of this character the liquid to be heated is usually maintained in continuous circulation and under pressure by means of a pump, not here shown. That is, the pump is pro-

vided with a discharge pipe which connects with the elbow 22, and the suction side of the pump is connected with the elbow 28. Thus there is a tendency for differential pressure, the pressure being highest in the chamber 19 and lowest in the chamber 21. This pressure variation increases the tendency for the liquid to by-pass from one chamber to another without passing through the tubes, but such a tendency is entirely overcome by maintaining the gaskets or packing strips in the manner here disclosed.

The principle of maintaining a packing gasket in engagement with its seat by means of fluid pressure is not limited to the specific application shown in Figs. 1 and 2, as it is equally applicable to the type of gasket shown at 40 in Fig. 1. For instance, in Fig. 4, the gasket 40a is shown as disposed adjacent the inner annular face 41 of the head B', and is retained in that position by a retainer ring 42 and lugs 43. In this position one face of the gasket will engage the tube sheet, while the opposite face will be exposed to the fluid under pressure, and as such will be forced against the tube sheet with sufficient pressure to prevent leakage between head B' and the tube sheet.

While certain features of my invention have been more or less specifically described and illustrated, I nevertheless wish it understood that changes may be resorted to within the scope of the appended claim, and that the materials and finish of the various parts employed may be such as the manufacturer desires, or various conditions of use demand.

Having thus described my invention, what I claim and desire to secure by Letters Patent is—

In a heat exchanger of the character described, a body member, a tube sheet secured at one end thereof, a plurality of heat-exchanging tubes secured in the tube sheet, through which a fluid under pressure is circulated, a removable head cooperating with the tube sheet, said head having a partition wall which divides the head into two chambers, said chambers diverting and causing a back-and-forth flow of the fluid through the tubes, and means for preventing leakage under the partition wall from one chamber to the other, said means comprising a bar disposed parallel to the wall and spaced therefrom, and a packing gasket disposed between the wall and the bar, said gasket having one face positioned to engage the tube sheet and the opposite face exposed to the fluid under pressure, so that the pressure exerted thereon will force the gasket against the seat.

EDWARD M. O'DONNELL.
